CLAIM

The ornamental design for a hockey blade and stick storage rack, as shown and described.

DESCRIPTION

FIG. 1 illustrates a perspective view of a hockey blade and stick storage rack incorporating my design.

FIG. 2 illustrates a right side view of the hockey blade and stick storage rack illustrated in FIG. 1 with the measuring step resting in a useable position outside the rack.

FIG. 3 illustrates a left side view of the hockey blade and stick storage rack illustrated in FIG. 1 with the measuring step resting in a useable position outside the rack.

FIG. 4 illustrates a front view of the hockey blade and stick storage rack illustrated in FIG. 1 with the measuring step resting in a useable position outside the rack.

FIG. 5 illustrates a rear view of the hockey blade and stick storage rack illustrated in FIG. 1 with the measuring step resting in a useable position outside the rack.

FIG. 6 illustrates a top view of the hockey blade and stick storage rack illustrated in FIG. 1 with the measuring step resting in a useable position outside the rack.

FIG. 7 illustrates a bottom view of the hockey blade and stick storage rack illustrated in FIG. 1 with the measuring step resting in a useable position outside the rack.

FIG. 8 illustrates a perspective view of the hockey blade and stick storage rack illustrated in FIG. 1 with the measuring step stored in an upright and storable position outside the rack; and,

FIG. 9 illustrates a perspective view of the hockey blade and stick storage rack illustrated in FIG. 1 with the measuring step stored within the rack.
